CONVERSION OF ALKYL NITRATES TO
CARBOXYLIC ACIDS

7 Claims

ABSTRACT OF THE DISCLOSURE

Alkyl nitrates are oxidized with nitric acid in the presence of a vanadate salt and an NO₂ or nitrite-containing initiator to yield carboxylic acids containing varying numbers of carbon atoms. Selectivity as between the carboxylic acid types produced is attained by selective control of the temperature at which the nitric acid oxidation is carried out.

BACKGROUND OF THE INVENTION

Field of the invention

This invention relates to the production of carboxylic acids, and more particularly, to the nitric acid oxidation of alkyl nitrates to yield a mixture of carboxylic acids of varying chain length.

Brief description of the prior art

It is known that alkyl nitrates derived from, for example, the nitric acid esterification of alcohols, can be converted to carboxylic acids by hydrolyzing the esters. A process of this type is disclosed in Schoenbrunn U.S. Pat. 3,284,494.

Brief description of the present invention

This invention provides a process for directly producing straight chain carboxylic acids from 1-alkyl nitrates by oxidation of the alkyl nitrates with nitric acid in the presence of a vanadate salt. The temperature of the reaction is controlled to selectively control the ratio of the several types of carboxylic acids yielded by the reaction. More specifically, the reaction is carried out at a temperature in the range of from about 20° C. to about 110° C. using nitric acid having a strength which is preferably from about 8 molar to about 21 molar. When the reaction is carried out at relatively low temperatures within the operating range, a predominance of carboxylic acid containing the same number of carbon atoms as contained by the alkyl nitrate reactant is present in the mixture of carboxylic acids produced by the reaction. When the reaction is carried out at relatively high temperatures within the range, the predominant carboxylic acid produced is one containing one less carbon atom than the number of carbon atoms contained in the starting alkyl nitrate.

An object of the invention is to provide a method for directly oxidizing alkyl nitrates to carboxylic acids.

Another object of the invention is to provide a method for selectively converting alkyl nitrate to a mixture of carboxylic acids of varying chain lengths.

Other objects and advantages of the invention will be apparent as the following detailed description of the invention is considered.

DETAILED DESCRIPTION OF A PREFERRED
EMBODIMENT OF THE INVENTION

In carrying out the nitric acid oxidation of alkyl nitrates to produce carboxylic acids, nitric acid having a strength of from about 8 molar to about 21 molar is employed. Preferably, the nitric acid has a strength of from about 12 molar to about 16 molar. The alkyl nitrates utilized in the oxidation reaction are preferably straight chain 1-alkyl nitrates. A vanadate salt promoter is utilized, and the reaction is carried out at a temperature in the range of

2

from about 20° C. to about 110° C. A nitrite compound or NO₂ is preferably used as a reaction-initiator, and is particularly effective when the reaction is carried out at relatively high temperatures within the described temperature range. The reaction time employed is from about 1 hour to about 4 hours, with a 2 hour total reaction time being preferred.

We have determined that the selectivity obtained as between the several types of carboxylic acids produced in the described oxidation reaction can be controlled by control of the temperature utilized when carrying out the reaction. Thus, when the reaction is carried out at relatively low temperatures (of from about 20° C. to about 60° C.) within the described temperature range, carboxylic acids which contain the same number of carbon atoms as the alkyl nitrate starting materials predominate in the mixture of carboxylic acids which is produced. When, on the other hand, a relatively high temperature (of from about 60° C. to about 110° C.) within the described range is employed, a mixture of carboxylic acids results from the oxidation, but in this case, the carboxylic acid containing one less carbon atom than the total number of carbon atoms in the alkyl nitrate material predominates in the product. Moreover, an increase in the amount of carboxylic acid containing two carbon atoms less than the carbon atom content of the starting material is also perceived to occur.

The following examples will serve to further illustrate the principles of the invention, but are not intended to be comprehensive statements of all the possible reactants or reactant conditions and parameters which may be employed in carrying out the process of the invention.

EXAMPLE 1

500 ml. of 15.4 molar nitric acid, 0.23 gram of ammonium vanadate and 6.9 grams of sodium nitrite were charged to a three-necked, round-bottom flask equipped with a condenser, thermometer, mechanical stirrer and addition funnel. The reaction mixture was then heated to 80° C., and 17 grams of octyl nitrate were then added to the reaction flask in a drop-wise fashion by the use of the addition funnel. The addition of the octyl nitrate was carried out over a period of 25 minutes. The reaction was then continued for a total period of two hours as measured from the start of the addition of the octyl nitrate to the flask.

A portion of the product mixture was then isolated by extraction with pentane, and the carboxylic acids extracted from the pentane solution with base. After treatment of the base solution with a mineral acid to free the carboxylic acids, the carboxylic acids were analyzed by addition of decanoic acid as an internal standard, followed by esterification and quantitative analysis of the esters by gas chromatography.

It was determined that 12.83 grams of the carboxylic acids were produced by the reaction, and that the product mixture contained 0.26 gram of neutral material which was found to be the octyl nitrate starting material. Analysis of the mixture of carboxylic acids showed the mixture to contain 8.21 weight percent of octanoic acid, 74.53 weight percent of heptanoic acid, and 4.39 weight percent of hexanoic acid.

EXAMPLE 2

A reaction flask equipped in the same way as described in Example 1 was charged with nitric acid, ammonium vanadate and sodium nitrite in the same quantities as described in Example 1. The reaction mixture was then heated to 40° C., and 16.68 grams of octyl nitrate were added drop-wise through the addition funnel. The reaction was then allowed to continue at 40° C. for a total reaction time of two hours, as measured from the time at which addition of the octyl nitrate was started.

After working up the product mixture in a manner described in Example 1, and completing analyses of the product mixture for carboxylic acids and neutral material, it was found that the product mixture contained a total carboxylic acid content of 5.55 grams. 10.35 grams of neutral material were produced, and this material was shown to be the starting octyl nitrate. The weight percent distribution of carboxylic acids in the product was 63.9 weight percent of octanoic acid, 27.9 weight percent of heptanoic acid, and 1.39 weight percent of hexanoic acid.

EXAMPLE 3

To a reaction flask fitted out in the manner described in Example 1 and containing 500 ml. of 15.4 molar nitric acid, 0.004 mole of ammonium vanadate and 2.4 mole of NO_2 were added. After heating the contents of the flask to $20^\circ \text{ C}.$, 47.09 grams of octyl nitrate were added drop-wise through the addition funnel. Heating of the reaction mixture was continued for a total reaction period of two hours. The product was worked up and analyzed and found to contain 0.45 gram of carboxylic acids and 45.6 grams of unreacted octyl nitrate. Of the carboxylic acids produced, 90.4 weight percent was octanoic acid and 4.7 weight percent was heptanoic acid.

EXAMPLE 4

To a reaction flask, made up with accessories as described in Example 1, 500 ml. of 15.4 molar nitric acid, 0.004 mole of ammonium vanadate and 2.4 mole of nitrogen dioxide were added. The temperature of the flask and its contents was then elevated to $60^\circ \text{ C}.$ and 47.1 grams of octyl nitrate were added in drop-wise fashion. After a total reaction period of one hour, the reaction was terminated and the contents of the flask allowed to cool. The products of the reaction were then worked up, separated and analyzed. A total amount of 26.1 grams of carboxylic acids were produced by the reaction, and 10.5 grams of neutral octyl nitrate were found in the reaction product mixture. The mixed carboxylic acids were found to contain 45 weight percent of heptanoic acid and 53.2 weight percent of octanoic acid.

From the foregoing description of the invention, it will have become apparent that mixed carboxylic acids, in which the distribution of the various acids within the mixture is controlled by control of the temperature at which the reaction is run, can be effectively produced by oxidizing alkyl nitrates, utilizing nitric acid as the oxidant. Although various reaction conditions have been herein described, and illustrative reactants have been set forth, it is to be understood that various changes and innovations can be made in the described reaction conditions and reactants without departure from the basic principles of the invention. Changes and innovations of this type which do not depart from the basic principles of the in-

vention are therefore deemed to be circumscribed by the spirit and scope of the invention except as the same may be necessarily limited by the appended claims or reasonable equivalents thereof.

5. What is claimed is:

1. A method for producing straight chain 1-alkane carboxylic acids comprising oxidizing straight chain 1-alkyl nitrates with nitric acid in the presence of a vanadate salt at a temperature of from about $20^\circ \text{ C}.$ to about $110^\circ \text{ C}.$

10. 2. The method defined in claim 1 wherein a reaction initiator selected from the group consisting of a nitrite compound and NO_2 is added to the reaction mixture.

15. 3. The method defined in claim 1 wherein the reaction is carried out at a temperature of about $20^\circ \text{ C}.$ to about $60^\circ \text{ C}.$ to produce a mixture of straight chain 1-alkane carboxylic acids in which the carboxylic acid containing a number of carbon atoms equal to the number of carbon atoms in the straight chain 1-alkyl nitrate starting material predominates.

20. 4. The method defined in claim 1 wherein the reaction is carried out at a temperature above $60^\circ \text{ C}.$ to thereby substantially increase the yield of straight chain 1-alkane carboxylic acids containing fewer carbon atoms than the straight chain 1-alkyl nitrate starting material.

25. 5. The method of producing straight chain 1-alkane carboxylic acids containing fewer than x number of carbon atoms which comprises heating a mixture of a straight chain 1-alkyl nitrate containing x carbon atoms, nitric acid having a strength of from about 12 molar to about 16 molar, a vanadate salt, and a nitrite salt to a temperature exceeding $60^\circ \text{ C}.$ for a period of about two hours.

30. 6. The method defined in claim 5 wherein said mixture is heated to a temperature of at least $80^\circ \text{ C}.$ for said period.

35. 7. The method defined in claim 5 wherein 15.4 molar nitric acid is employed.
